(57) **CLAIM**

The ornamental design for an adjustable tripod, as shown and described.

DESCRIPTION

FIG. 1 is a front view of an adjustable tripod in a stowed configuration.

FIG. 2 is a back view of an adjustable tripod in a stowed configuration.

FIG. 3 is a top view of an adjustable tripod in a stowed configuration.

FIG. 4 is a bottom view of an adjustable tripod in a stowed configuration.

FIG. 5 is a left side view of an adjustable tripod in a stowed configuration.

FIG. 6 is a right side view of an adjustable tripod in a stowed configuration.

FIG. 7 is a perspective view of an adjustable tripod in a stowed configuration.

FIG. 8 is a front view of an adjustable tripod in a deployed configuration.

FIG. 9 is a back view of an adjustable tripod in a deployed configuration.

FIG. 10 is a top view of an adjustable tripod in a deployed configuration.

FIG. 11 is a bottom view of an adjustable tripod in a deployed configuration.

FIG. 12 is a left side view of an adjustable tripod in a deployed configuration.

FIG. 13 is a right side view of an adjustable tripod in a deployed configuration.

FIG. 14 is an upper perspective view of an adjustable tripod in a deployed configuration; and,

FIG. 15 is a lower rear perspective view of an adjustable tripod in a deployed configuration.
